UNITED STATES PATENT OFFICE.

GEORGE WALKER, OF NEWTON CENTER, MASSACHUSETTS.

COMPUTING-MACHINE.

1,098,856.

Specification of Letters Patent.

Patented June 2, 1914.

Application filed July 25, 1912. Serial No. 711,504.

To all whom it may concern:

Be it known that I, GEORGE WALKER, a citizen of the United States, and resident of Newton Center, in the county of Middlesex and State of Massachusetts, have invented new and useful Improvements in Computing-Machines, of which the following is a specification.

This invention relates to a computing machine, and particularly to a machine for adding and subtracting.

The invention consists principally in novel and improved tripping or carrying mechanism of simplified and improved construction and operation; in means whereby the machine may be automatically placed in condition for either adding or subtracting the amounts represented by the keys depressed, by merely shifting a single hand lever; in mechanism for automatically throwing the type wheels into the proper position for printing the sum, whenever the "sum key" is depressed, regardless of whether said hand lever stands in adding position or in subtracting position; and in adapting said tripping or carrying mechanism to computation according to non-decimal systems as well as to decimal systems. In my present device the tripping or carrying is in no way dependent upon the action of springs but is performed positively and directly by the power which operates the machine in response to the key action. My improved carrying mechanism also includes a block or stop which automatically limits the movement of the tripping parts, thus positively arresting the movement of the wheels actuated thereby at the proper predetermined point. When said hand lever which determines whether the machine will add or subtract, is thrown to adding position, the depression of the keys without further attention on the part of the operator will automatically add and print the amounts represented by the keys depressed, and when said hand lever is thrown to subtracting position, the depression of the keys without further attention on the part of the operator will automatically subtract and print the amounts represented by the keys depressed.

Other features will hereinafter be mentioned and particularly pointed out in the claims.

For the purpose of illustration, I will describe the present invention as applied to the computing machine shown in Letters

Patent of the United States No. 996,173, granted to me June 27, 1911, but it will be understood that the invention is not limited to that particular machine but is of general application.

In the accompanying drawings which illustrate certain embodiments of the invention, and show only such parts of the computing machine of my said former patent as are essential to a clear understanding of the invention,—Figure 1 is a side view of my improved carrying mechanism, and the devices for adding and subtracting, for operating according to the decimal system, applied to the gear wheels which operate the type wheels or number wheels of the machine, the parts being shown in subtracting position; Figs. 2 and 3 are fragmentary side views showing the changes necessary to adapt the device to computations according to a non-decimal system,—the English money system being used as an example; Fig. 4 is a detail view of a part of the carrying mechanism hereinafter described; Fig. 5 is a fragmentary view showing the position of certain of the parts of Fig. 1 when shifted to adding position; and Figs. 6 and 7 are detail views showing the mechanism for shifting the parts from adding to subtracting positions or vice versa.

Referring to the drawings, 1, 1', etc., represent the main gear wheels or number-wheel gears of the machine, journaled on shaft 4, and meshing with gear wheels 2, 2^A, etc., which respectively carry the number-wheels or type wheels 3, 3^A, 3^B, etc., journaled on shaft 5. Said gear wheels and number-wheels may be constructed and arranged as shown in my said former patent. Instead of the tripping or carrying mechanism therein shown, my improved tripping or carrying mechanism, as herein exemplified, comprises the following parts: a stud 733 (Fig. 6) projects from the inside of one of the side frames of the machine, through a hole in the rocking piece 732, which swings on stud 733. Another stud 739 also projects from the inside of said side frame through a hole in the rocking piece 738, which swings on stud 739. Parts 732 and 738 are connected by rod 737. Stud 734 projects from the inside of said side frame into the path of swinging piece 732 acting as a stop to limit the movement of part 732. A spring 735, connecting the end of swinging piece 732 and a pin 736 projecting from the inside of

said frame, tends to urge the nose 732^a of piece 732 toward stud 734. The lower end of swinging piece 738 is connected by rod 740 with arm 741, which is solidly fastened to shaft 742, extending between side frames of the machine with its ends turning therein. Duplicates of the foregoing parts are mounted just inside the opposite side frame of the machine and are shown in Fig. 7, 732' and 738' representing swinging pieces like parts 732 and 738; nose, 732^b corresponding to 732^a; studs 733', 739' and 734' corresponding to studs 733, 739 and 734; connecting rod 737' corresponding to rod 737; and spring 735' and pin 736' corresponding to spring and pin 735 and 736. The corresponding parts at the two sides of the machine are arranged directly opposite one another. Rod 740' corresponding to rod 740, connects the lower end of piece 738' with arm 741' which is fast on shaft 742.

Manually operated means for actuating pieces 734 and 734', and 738 and 738', are provided, consisting of a hand lever or shipper 760 which turns on shaft 74 and engages pin 762 on arm 761 solidly fastened to shaft 742 close to lever 760. The lever 760 projects through a slot *d* in the cover or top frame *D* of the machine and is made with sufficient lateral resiliency to spring into and engage notches or shoulders provided in the sides of said slot in a manner well understood for holding said lever 760 at the extremes of its forward and backward throw.

In the position shown in Fig. 7, the lever 760 is thrown forward, in the direction of the arrow to the limit of its movement in that direction. Such forward movement of lever 760 swings arm 761 by pin 762 in the same direction, thereby rotating shaft 742 and swinging the rocking parts 732 and 732', and 738 and 738' in a clockwise direction, as viewed in the drawings. When the lever 760 swings back in the opposite direction from the arrow, spring 735 and 735' will swing said rocking pieces in a counter-clockwise direction, the pin 762 following the side of lever 760, against which it is pressed by the action of said springs.

Extending between rocking pieces 738 and 738' are shafts 5 and 725; and extending between rocking pieces 732 and 732' are shafts 728 and 731. The series of gear wheels 2, 2^A, etc., carrying type wheels 3, 3^A, etc., are assembled on shaft 5. A set of intermediate gear wheels 724, 724^A, etc., one meshing with each of said gear wheels 2, 2^A, etc., are assembled on shaft 725. Said two sets of gear wheels are adapted to engage the number-wheel gears, 1 1', etc., one set at a time, so that when rocking pieces 738 and 738' are swung to their extreme position in a counter-clockwise direction the gear wheels 2, 2^A, etc., will directly engage the number-wheel gears 1, 1', etc., (as shown in Fig. 5),

said intermediate gears 724, 724^A, etc., standing clear of the number-wheel gears; and when said rocking pieces are swung to their opposite extreme position, in a clockwise direction, said gear wheels 2, 2^A, etc., will be 70 in train with said number-wheel gears 1, 1', etc., through said intermediate gears 724, 724^A, etc., (as shown in Fig. 1), thus reversing the direction of rotation of the type wheels 3, 3^A, etc., assuming the rotation of 75 the number-wheel gears 1, 1', etc., to be always in the same direction. Assembled on shaft 728 is a set of gear wheels 726, 726^A, etc., one for each of said number-wheel gears 1, 1', etc., except the last in the series 80 progressing from the unit column upward to the columns of higher order. On shaft 731 is assembled a set of gear wheels 729, 729^A, etc., meshing with gear wheels 726, 726^A, etc., there being one such gear wheel of the 729 set 85 for each gear wheel of the 726 set. These two sets of gear wheels, which may be termed the carrying or tripping gears, are adapted to engage the main gears 1, 1', etc., one set at a time, the gear wheels of the 726 90 set being in mesh with said number-wheel gears when the rocking parts 732 and 732' are swung in a counter-clockwise direction, and the gear wheels of the 729 set being in mesh with the number-wheel gears when 95 said rocking parts are swung in a clockwise direction.

The gear wheels of the several sets 2, 724, 726 and 729 are all alike. Each gear wheel 726 carries fastened to its side a tooth or 100 projection 727 (best shown in Fig. 1), and each gear wheel 729 carries fastened to its side a tooth or projection 730 (best shown in Fig. 5). Shafts 750 and 751 extend between the side frames of the machine, at 105 either side of said carrying gears. Arm 749 swings on shaft 750, arm 752 swings on shaft 751, and an oscillating bar 748 is hung on the lower ends of arms 749 and 752, to swing between main gear wheel 1 and the adjacent 110 main gear wheel 1'. Bar 748 is in the same vertical plane with teeth 727 and 730. On the end of bar 748 is hung a double ended pawl 747, which is in the same plane with and operates gear wheel 1'. There is a bar 115 748 and pawl 747 co-operating with each set of carrying gears 726, 729.

A set of springs 744 hung on rod 745, which is supported between the side frames of the machine, with one end engaging rod 120 743, also supported between said side frames, and the other end engaging pawls 747, tends to press the upper ends of pawls 747 against the teeth of the number-wheel gears 1, 1', etc., and at the same time to throw the bars 125 748 toward the right into the position shown in the drawings, with their ends resting against rod 746, which extends between the side frames of the machine and acts as a stop for bars 748.

Each gear wheel lock 18 (of which there is one for each number-wheel gear 1, 1', etc., as described in my said former patent) is provided with a finger 18^A projecting upward back of and in engagement with the end of arm 752. Each bar 748 has two upwardly projecting teeth 748^A and 748^B (best shown in Fig. 4). Tooth 727 of gear wheel 726 operates against tooth 748^A, and tooth 730 of gear wheel 729 operates against tooth 748^B.

Standard 759 (Fig. 7) mounted solidly on the base of the machine frame, carries stud 758 on which is pivoted bell crank lever 756. A pin 757 projects from the lower arm of bell crank 756 under rod 167. The upper arm of bell crank 756 is connected by rod 755 with arm 754, which is fastened solidly on shaft 742 over bell crank 756.

As described in my said former patent, the type wheels carry on their peripheries, a series of types or numerals from "0" to "9" inclusive arranged counter-clockwise and when in normal position before the machine has been operated the "0" type will be in position A, (Fig. 1).

Adding.—When the machine is to be operated for adding, lever 760 (Fig. 7) is thrown to the left as viewed in the drawings 30 swinging gear wheels 726 and 2 into mesh with the number-wheel gears 1, as shown in Fig. 5. The type wheels or number wheels 3 will then be actuated directly from said number-wheel gears, as in my said former 35 patent, and when number-wheel gear 1 is rotated counter-clockwise, by the depression of a key, as explained in my said former patent, the amount represented by the key will be added on said type wheel. At the 40 same time gear wheel 726 will be turned by number-wheel gear 1, the same number of teeth as gear wheel 2. When nine has been added on type wheel 3, the tooth 727 will have been turned to the point where it will 45 rest against the face of tooth 748^A of bar 748. If now a key of the same column is depressed, carrying type wheel 3 to "0" or beyond, the tooth 727 will swing bar 748 endwise toward the left, thereby causing 50 pawl 747 to turn the next gear wheel 1' of higher order, one tooth, and adding one on the type wheel of the next higher column. At the end of the key stroke, bar 748 will fly back into normal position against stop 746, 55 under the influence of spring 744. It will be noticed that there is a slight space between the end of pawl 747 and the tooth of gear wheel 1 against which it is to operate, thus affording a little 60 lost motion after the bar 748 starts to swing to the left. While pawl 747 is traveling this space, arm 752 acts on the finger 18^A of lock 18, lifting said lock out of the gear wheel in time to allow the gear wheel to be rotated 65 when pawl 747 reaches the tooth of said

gear wheel. At the end of the movement of pawl 747 the right hand or lower end of said pawl swings into engagement with the teeth of gear wheel 1 and acts as a block or stop to prevent said gear wheel 1 from being rotated more than the distance of one tooth during said tripping or carrying operation.

Subtracting.—In order to place the machine in condition for subtracting instead of adding, all that need be done by the operator is to throw hand lever 760 in the direction of the arrow to the position shown in

Fig. 7. The parts will then be in the positions shown in Figs. 1, 6 and 7, with gear wheels 724 and 729 in mesh with gear wheel 80 1, and gear wheels 2 and 726 out of mesh with gear wheel 1. If now a key is depressed, gear wheel 1, still rotating counter-clockwise as described in my said former

patent, will act through intermediate gear 85 724 to turn type wheel 3 counter-clockwise, that is, in a direction opposite to that taken when the machine is adding, and instead of turning the types forward from "0" to "9" will turn them backward from 90

"9" toward "0", thus subtracting on the type wheel the amount represented by the key being operated. In subtracting, as will be understood, the carrying of the gear wheel and type wheel of higher order from 95 a wheel of lower order, must take place as the latter is passing from "0" to "9" instead of from "9" to "0" as in adding.

The carrying for subtraction is accomplished by the tooth 748^B, the tooth 730 and 100 gear wheel 729. It will be observed that when the type wheel 3 stands with "0" in printing position A, tooth 730 on gear wheel 729 is in position against tooth 748^B of bar 748. If gear wheel 1 is again rotated a 105 distance, for example of one tooth, bar 748 will be swung by tooth 730, and pawl 747 will turn the next gear wheel 1', a distance of one tooth, thereby subtracting one on type wheel of the next higher order. Thus 110 the carrying tooth 730 for subtracting is adjusted to carry the gear wheel of higher order when its own type wheel is passing from "0" to "9", while the carrying tooth 727 for adding is adjusted to carry the gear 115 wheel of higher order when its own type wheel is passing from "9" to "0".

It will be observed that when either gear wheel 726 or 729 is in mesh with gear wheel 1, it rotates in a clockwise direction and the 120 tripping tooth 727 or 730 as the case may be, travels toward the teeth of bar 748, but when either gear wheel 726 or 729 is out of mesh with gear wheel 1, it rotates counter-clockwise and the carrying tooth 727 or 730, as the case may be, recedes from the point where the carrying is effected. Thus the carrying teeth are automatically maintained in position to trip or carry at the proper point whenever either set of carrying wheels, 130

whether for adding or subtracting, is rocked into mesh with the number-wheel gears 1 by the hand lever 760. By this mechanism the operation of the keys, always in the same manner, automatically performs addition or subtraction as described, without further attention on the part of the operator than throwing the lever 760 forward or backward. The top frame or cover D may be marked "Add" and "Subtract", if desired, opposite the two positions of lever 760, to indicate the direction in which the lever 760 is to be thrown to accomplish the desired result.

In a machine thus constructed for adding and subtracting, it will be seen by reference to the parts shown in Fig. 1, and by reference to my said former Patent No. 996,173 showing the relation between the type wheels and the printing hammers and paper carrying devices, that in order to bring the type wheels 3 into proper position to print the sum, that is, in position nearest the hammers and in alinement therewith, the type wheels should be thrown away from gear wheels 1 to subtracting position (as in Fig. 1) whenever the sum is to be printed. Of course, if the machine is already in subtracting position when the result is printed, no change of position is necessary; but if the machine is at the time being used for adding, it is necessary that the type wheels be shifted to subtracting position. This is accomplished automatically whenever the "sum key" for operating the hammers in unison to print the sum is depressed, by the following mechanism: As described in my said former patent, whenever the "sum key" is depressed, the rod or link 167 for actuating the hammers, moves in the direction of the arrow in Fig. 7. Assuming now that the lever 760 is thrown to adding position, that is, toward the left, and that the tripping gears and type wheels are consequently in the position shown in Fig. 5, arm 761 will be thrown to the left under the influence of springs 735 and 735' with pin 762 resting against lever 760, and bell crank 756 will be swung in the same direction throwing pin 757 toward the projection 167^A on rod 167 (Fig. 7). If the "sum key" is depressed with the parts in this position, the projection 167^A will engage pin 757 and swing bell crank 756 so as to carry all the parts excepting lever 760 into the positions shown in Figs. 1, 6 and 7, thus bringing the type wheels 3 into proper position for printing the sum. When the "sum key" is released, permitting rod 167 to return to its initial position, the other parts will automatically return to the adding position under the influence of springs 735 and 735', so that the adding process may be continued exactly where it left off, without requiring any preliminary adjustment or manipula-

tion by the operator. If the result is to be printed with the lever 760 already in subtracting position, as shown in Fig. 7, the movement of rod 167 in response to the depression of the "sum key" will not actuate bell crank 756, but merely move projection 167^A idly up to pin 757. Therefore, rod 167 will merely actuate the hammers as described in my former patent without affecting the mechanism which controls the adding and subtracting position of the other parts. Another reason exists for always having the number wheels brought to the same position when the sum is printed, in addition to the necessity of bringing them close to the hammers, namely: the alinement lock, consisting of bar 700 on arms 700^A and 700^B, for engaging notches in the number wheels to insure their true alinement. This alinement lock is actuated by rod 702, spring 701 and arm 703 fast on rock shaft 105. As these parts constitute the subject of another application to be filed simultaneously herewith, they need not be more fully described herein. Thus the machine may be thrown into adding or subtracting position as desired, by merely shifting lever 760, and yet whenever the "sum key" is depressed, which actuates rod 167, the type wheels will be automatically thrown to the proper position for printing the sum (if they are not already in that position) and will be automatically restored again to their initial position.

Non-decimal system.—The machine thus far described, as exemplified particularly in Figs. 1 and 5, is a machine for computing by the decimal system. The invention, however, is equally well adapted for computation by any non-decimal system, and for the purpose of illustration I will describe the modifications necessary to adapt the invention to compute according to the English money system of pounds, shillings and pence.

Fig. 2 illustrates the mechanism for adding and subtracting in the pence column. The keyboard and other parts of the machine not directly connected with the present invention, may be as shown in that part of my said former patent describing the English money machine. Gear wheels 2^A, 724^A, 726^A and 729^A (Figs. 2 and 3) corresponding to the similar parts in other figures, have twelve teeth each, instead of ten, and type wheel 3^A also has twelve numerals, from "0" to "11" inclusive. The tripping teeth are adjusted to operate the units column of the shillings wheels, when the pence type wheel 3^A passes from "11" to "0" for adding, and from "0" to "11" for subtracting. In other respects the construction and operation of the parts is the same as in the decimal system mechanism already described. Fig. 3 shows the corresponding

120

125

130

parts in the tens column of the shillings wheels. There being twenty shillings in a pound, there are two shillings wheels and two shillings columns, the units shillings 5 wheel being numbered from "0" to "9" as in the regular decimal system, and the tens shillings wheel 3^B being provided alternately with the numeral "1" and blank spaces as shown in Fig. 52 of my said former 10 Patent 996,173. Gear wheel 726 carries on its side five tripping teeth 727^A, and gear wheel 729 also carries on its side five tripping teeth 730^A. It will be understood that at the side of the shillings columns are the 15 pounds columns which are constructed and operated according to the regular decimal system already described. Whenever gear wheel 1 (Fig. 3) is moved a distance of two teeth (the carrying teeth of gear wheels 20 726 and 729 being spaced apart the distance of two gear teeth) the unit wheel of the pounds column will be rotated one tooth or one space for the addition or subtraction of one in that column, so that whenever the 25 combined shillings type wheels pass from "19" to "0" for adding, or from "0" to "19" for subtracting, the units pounds column is rotated either forward or backward one step, thereby either adding or subtracting one in that column. In other respects the operation of the device is the same as 30 already described.

Should it be desired to use my new form of tripping or carrying mechanism in an 35 adding machine which is not also a subtracting machine, gear wheels 726 may be mounted on a fixed shaft instead of an oscillating or moving shaft, that is, shaft 728 may be fixed in the side frames of the 40 machine so that gears 726 are permanently in mesh with number wheel gears 1, in the position shown in Fig. 5. Gear wheels 729, having no office to perform in the adding operation, may be dispensed with. Intermediate gear wheels 724 may also be dispensed with, and the gears 2 of number wheels 3 will be permanently in mesh with gear 45 wheels 1, as shown in my said former patent. Also the hand lever 760 and the parts 50 operated thereby will be omitted since the tripping gear wheels and the number wheels are not to be rocked but are permanently in adding position. The tripping or carrying will then be performed through the carrying 55 gears 726 and bars 748, as already described.

In a tripping or carrying mechanism constructed as herein described, either for adding and subtracting, or for adding alone, the pawl 747 will not interfere with the free 60 and independent rotation of gear wheel 1', which the pawl operates in carrying, so that said gear wheel 1' may be operated directly from the keys of the machine; nor will the rotation of gear wheel 1' affect gear wheel 1 65 since the pawl will drag idly over the teeth

of gear wheel 1' when the latter is rotated from the keys.

Inasmuch as multiplication is a species of addition and division is a species of subtraction, it will be understood that the mechanisms herein described are applicable also for multiplying and dividing machines. 70

When the above described carrying mechanism is used instead of that shown in my said former Patent No. 996,173, which contains a cam wheel (see cam wheel 141, Fig. 54 of my said patent), I provide pins or studs 753 for actuating lever 180, which controls the hammer blocking devices (not shown). The action of said studs in place 80 of the cam teeth will be obvious by reference to my said patent, and as the hammer blocking mechanism forms no part of the present invention it need not here be more explicitly described. 85

I claim:

1. In combination with the number-wheel gears of a computing machine having locks normally holding said gears against rotation, a carrying device comprising a tripping gear in mesh with one of said number-wheel gears, and mechanism actuated by said carrying gear adapted to carry a number-wheel gear of different order and to unlock the lock engaging such number-wheel gear during said carrying operation. 95

2. In combination with the number-wheel gears of a computing machine, a carrying device comprising a tripping gear in mesh with one of said number-wheel gears, mechanism between said carrying gear and a number-wheel gear of different order adapted to carry the latter, said mechanism also adapted to permit the independent rotation of the number-wheel gear carried thereby, a movable stop adapted to arrest the number-wheel gear being carried at the end of its predetermined carrying movement, and locks normally holding said number-wheel gears against rotation, said tripping mechanism also adapted automatically to unlock the lock engaging the number-wheel gear being carried during its carrying movement. 105 110

3. In combination with the number-wheel gears of a computing machine, a carrying device comprising a carrying gear in mesh with one of said number-wheel gears, and mechanism between said carrying gear and a number-wheel gear of different order, adapted to carry the latter at a predetermined point in the rotation of said carrying gear, said mechanism also being adapted to permit the independent rotation of the number-wheel gear carried thereby, irrespective of the position of the carrying mechanism, 115 and means adapted automatically to restore said carrying mechanism to its initial position at the end of each carrying operation. 120 125

4. In combination with the number-wheel gears of a computing machine having locks 130

- normally holding said gears against rotation, a carrying device comprising a carrying gear in mesh with one of said number-wheel gears, an oscillating bar at the side of 5 each number-wheel gear, a projection on said carrying gear to actuate said oscillating bar, a pawl actuated by said oscillating bar adapted to carry a number-wheel gear of different order, and connection between said 10 bar and the lock of the gear being carried to unlock said lock during the carrying operation.
5. In combination with the number-wheel gears of a computing machine, a carrying 15 device comprising a tripping gear in mesh with one of said number-wheel gears, an oscillating bar at the side of such number-wheel gear, swinging arms on which said bar is pivotally hung to provide endwise oscillation of said bar, a projection on said carrying gear to actuate said oscillating bar, and a pawl actuated by said oscillating bar adapted to carry a number-wheel of different 20 order.
25. 6. In combination with the number-wheel gears of a computing machine, a carrying device comprising a tripping gear in mesh with one of said number-wheel gears, an endwise oscillating bar at the side of such 30 number-wheel gear, a projection on said carrying gear to actuate said oscillating bar, a pawl actuated by said oscillating bar adapted to carry a number-wheel of different order, and a lock normally holding the last 35 named number-wheel gear against rotation and disengaged therefrom by said bar during said carrying operation.
7. In combination with the number-wheel 40 gears of a computing machine having locks normally holding said gears against rotation, a carrying device comprising a carrying gear in mesh with one of said number-wheel gears, and mechanism actuated by said carrying gear adapted at a predetermined point in its rotation to actuate a number-wheel gear of different order, and to unlock the lock engaging such number-wheel gear during said carrying operation, said mechanism being so timed as to withdraw 45 said lock before the number-wheel gear engaged thereby is rotated.
8. In combination with the number-wheel 50 gears of a computing machine, a carrying device comprising a tripping gear in mesh with one of said number-wheel gears, an endwise oscillating bar at the side of such number-wheel gear, a projection on said carrying gear to actuate said oscillating bar, a pawl actuated by said oscillating bar adapted to carry a number-wheel gear of different 55 order, and a lock normally holding the last named number-wheel gear against rotation and disengaged therefrom by said bar during 60 said carrying operation, the action of said lock and said pawl being relatively so timed that the withdrawal of the lock will begin before the pawl rotates said number-wheel gear.
9. In combination with the main number-wheel gears of a computing machine, said 70 gears adapted always to rotate in the same direction, a set of number-wheels actuated respectively by said main gears, each number-wheel bearing on its periphery a series of numerals, means to reverse the direction of rotation of said number-wheels without reversing the direction of rotation of the main gears, said number-wheels adapted to perform addition when rotated in one direction and subtraction when rotated in the opposite direction, and carrying devices adapted respectively to carry number-wheel gears of different order when their corresponding number-wheels, rotating in adding direction, pass from the end to the beginning of said 80 series of numerals, and rotating in subtracting direction; pass from the beginning to the end of said series of numerals.
10. In combination with the main number-wheel gears of a computing machine, a 90 series of number-wheels actuated respectively by said main gears, means to reverse the direction of rotation of said number-wheels without reversing the direction of rotation of said main gears, said number-wheels adapted to perform addition when rotated in one direction and subtraction when rotated in the opposite direction, and two sets of carrying gears engaging said 95 main gears one set at a time, each gear of one set adapted to carry a main gear of different order when the number-wheels are rotating in one direction, and each gear of the other set adapted to carry a main gear of different order when the number-wheels 100 are rotating in the opposite direction.
11. In combination with the main number-wheel gears of a computing machine, a series of number-wheels actuated respectively by said main gears, means to reverse 110 the direction of rotation of said number-wheels without reversing the direction of rotation of said main gears, said number-wheels adapted to perform addition when rotated in one direction and subtraction when 115 rotated in the opposite direction, and two sets of carrying gears engaging said main gears one set at a time, each gear of one set adapted to carry a main gear of different order when the number-wheels are rotating 120 in one direction, and each gear of the other set adapted to carry a main gear of different order when the number-wheels are rotating in the opposite direction, and connection between said carrying gears and said 125 number-wheels, adapted automatically to shift the carrying gears to positions appropriate to the direction of rotation of the number-wheels.
12. In combination with the main num- 130

- ber-wheel gears and number-wheels of a computing machine, a series of pairs of gears adapted to engage their respective main gears one at a time to rotate the number-wheels, the gears of each pair being in mesh with each other and shiftable into and out of mesh with their corresponding main gears, whereby said number wheels may, by shifting said pairs of gears, be rotated in either direction, to perform addition or subtraction, without reversing the direction of rotation of the main gears.
13. In combination with the main number-wheel gears and number-wheels of a computing machine, a series of pairs of gears adapted to engage their respective main gears one at a time to rotate the number-wheels, the gears of each pair being in mesh with each other and shiftable into and out of mesh with their corresponding main gears, whereby said number wheels may, by shifting said pairs of gears, be rotated in either direction, to perform addition or subtraction, without reversing the direction of rotation of the main gears, and carrying devices adapted respectively to carry number-wheels gears of different order when their corresponding number-wheels, rotating in adding direction, pass from the end of the beginning of the series of numerals on the number-wheels, and rotating in subtracting direction, pass from the beginning to the end of said series of numerals.
14. In combination with the main number-wheel gears of a computing machine, a set of number-wheels, two sets of gears in mesh with each other adapted to engage said main gears one set at a time, to rotate the number wheels in either direction, and two sets of carrying gears engaging said main gears one set at a time, each carrying gear of one set adapted to carry a main gear of different order when the number-wheels are rotating in one direction, and each carrying gear of the other set adapted to carry a main gear of different order when the number-wheels are rotating in the opposite direction.
15. In combination with the main number-wheel gears of a computing machine, a set of number-wheels, two sets of gears in mesh with each other adapted to engage said main gears one set at a time, to rotate the number-wheels in either direction, and two sets of carrying gears engaging said main gears one set at a time, each carrying gear of one set adapted to carry a main gear of different order when the number-wheels are rotating in one direction, and each carrying gear of the other set adapted to carry a main gear of different order when the number-wheels are rotating in the opposite direction, and connection between the sets of gears which rotate the number-wheels and the sets of carrying gears, adapted to shift said sets of gears in unison, thereby bringing the appropriate sets of gears into mesh with said main gears at the same time.
16. In combination with the main number-wheel gears of a computing machine, a series of number-wheels having gears fast thereto, shiftable into and out of mesh with said main gears and adapted to rotate the number-wheels in one direction when in mesh with said main gears, intermediate gears in mesh with said gears on the number-wheels and also shiftable into and out of mesh with said main gears and adapted when in mesh with said main gears to rotate said number-wheels in reverse direction, two sets of carrying gears in mesh with each other and adapted to engage said main gears one set at a time, the gears of one set adapted respectively to carry main gears of different order when the number-wheels are rotating in one direction, and the gears of the other set adapted respectively to carry main gears of different order when the number-wheels are rotating in the opposite direction.
17. In combination with the main number-wheel gears of a computing machine, a rocker comprising two shafts extending across said main gears, a set of number-wheels having gears fast thereto, assembled on one of said shafts, and a set of intermediate gears meshing with the gears fast on the number-wheels, assembled on the other shaft, said sets of gears adapted to engage the main gears one set at a time by swinging said rocker, thereby reversing the direction of rotation of the number-wheels, a second rocker comprising two shafts extending across the said main gears, each carrying a set of carrying gears, the gears of one set meshing respectively with the gears of the other set and adapted to engage the main gears one set at a time by swinging the last named rocker, one set of said carrying gears adapted to carry the main gears when the number-wheels are rotating in one direction, and the other set of carrying gears adapted to carry the main gears when the number-wheels are rotating in the opposite direction.
18. In combination with the main number-wheel gears of a computing machine, a rocker comprising two shafts extending across said main gears, a set of number-wheels having gears fast thereto, assembled on one of said shafts, and a set of intermediate gears meshing with the gears fast on the number-wheels, assembled on the other shaft, said sets adapted to engage the main gears one set at a time by swinging said rocker, thereby reversing the direction of rotation of the number-wheels, a second rocker comprising two shafts extending across the said main gears, each carrying a set of carrying gears, the gears of one set meshing respectively with the gears of the

other set and adapted to engage the main gears one set at a time by swinging the last named rocker, one set of said carrying gears adapted to carry the main gears when the 5 number-wheels are rotating in one direction, and the other set of carrying gears adapted to carry the main gears when the number-wheels are rotating in the opposite direction, said rockers being connected to swing in 10 unison, thereby bringing the appropriate sets of gears carried by the two rockers into mesh with said main gears at the same time.

19. In combination with the main number-wheel gears of a computing machine, a 15 set of number-wheels actuated respectively by said main gears, each number-wheel bearing on its periphery a series of numerals, means to reverse the direction of rotation of said number-wheels, said number-wheels 20 adapted to perform addition when rotated in one direction and subtraction when rotated in the opposite direction, and carrying devices adapted respectively to trip number-wheel gears of different order when their 25 corresponding number-wheels, rotating in adding direction, pass from the end to the beginning of said series of numerals, and rotating in subtracting direction, pass from the beginning to the end of said series of 30 numerals, and a single shipper for reversing the number-wheels and the carrying devices.

20. In combination with the main number-wheel gears of a computing machine, a 35 series of number-wheels actuated respectively by said main gears, means to reverse the direction of rotation of said number-wheels without reversing the direction of rotation of said main gears, said number-wheels 40 adapted to perform addition when rotated in one direction and subtraction when rotated in the opposite direction, and two sets of carrying gears engaging said main gears one set at a time, each gear of 45 one set adapted to carry a main gear of a different order when the number-wheels are rotating in one direction, and each gear of the other set adapted to carry a main gear of different order when the number-wheels 50 are rotating in the opposite direction, and a single shipper for reversing the number-wheels and the carrying gears.

21. In combination with the main number-wheel gears of a computing machine, a 55 rocker comprising two shafts extending across said main gears, a set of number-wheels having gears fast thereto, assembled on one of said shafts, and a set of intermediate gears in mesh with said gears fast 60 to the number-wheels, assembled on the other shaft, said sets adapted to engage the main gears one set at a time by swinging said rocker, thereby reversing the direction of rotation of the number-wheels, a second 65 rocker comprising two shafts extending

across the said main gears, each carrying a set of tripping gears, the gears of one set meshing respectively with the gears of the other set and adapted to engage the main gears one set at a time by swinging the last 70 named rocker, one set of said carrying gears adapted to carry the main gears when the number-wheels are rotating in one direction, and the other set of carrying gears adapted to carry the main gears when the number-wheels are rotating in the opposite direction, and a single shipper adapted to shift said rockers in unison, to bring the appropriate sets of gears carried by the two rockers into 75 mesh with said main gears at the same time.

22. In combination with the main number-wheel gears of a computing machine, a rocker comprising two shafts extending across said main gears, a set of number-wheels having gears fast thereto, assembled on one of said shafts, and a set of intermediate gears in mesh with said gears fast to the number-wheels, assembled on the other shaft, said sets adapted to engage the main 80 gears one set at a time by swinging said rocker, thereby reversing the direction of rotation of the number-wheels, a second rocker comprising two shafts extending across the said main gears, each carrying a set of carrying gears, the gears of one set meshing respectively with the gears of the other set and adapted to engage the main 85 gears one set at a time by swinging the last named rocker, one set of said carrying gears adapted to carry the main gears when the number-wheels are rotating in one direction, and the other set of carrying gears adapted to carry the main gears when the number-wheels are rotating in the opposite direction, and printing-hammer actuating mechanism adapted when operated, automatically to swing said number-wheels to their position 90 away from the main gear wheels.

23. In combination with the main number-wheel gears of a computing machine, carrying devices suitable for both adding and subtracting operations, comprising two carrying gears meshing with each other and adapted to engage one of said main gears 100 one at a time, an oscillating bar actuating a pawl adapted to carry a main number-wheel gear of different order, and projections carried by said carrying gears each adapted at a predetermined point in the rotation of its gear to actuate said bar to cause the pawl to carry the main gear of different order when its own carrying gear is in mesh with the main gear.

24. In combination with the main number-wheel gears of a computing machine, carrying devices suitable for both adding and subtracting operations, comprising two carrying gears meshing with each other and adapted to engage one of said main gears 110 115 120 125 130

one at a time, an oscillating bar actuating a pawl adapted to carry a main number-wheel gear of different order, two projections on said bar, and projections carried by said carrying gears, each adapted at a predetermined point in the rotation of its own gear to engage one of said projections on said bar and thereby actuate said bar and pawl when its own carrying gear is in mesh with the main gear, and to clear such projection on the bar when its own gear is out of mesh with the main gear.

25. In combination with the main number-wheel gears of a computing machine, locks normally holding said main gears immovable, and carrying devices suitable for both adding and subtracting operations, comprising two carrying gears meshing with each other and adapted to engage one

of said main gears one at a time, an oscillating bar actuated by either of said carrying gears when in mesh with its main gear, a pawl actuated by said bar adapted when operated to carry a main number-wheel gear of different order and positively to arrest the same at the end of its predetermined carrying movement, and means operated by said bar to unlock the lock of the main gear being carried during said carrying operation, and means to restore said bar, pawl and lock to their initial positions at the end of each carrying operation.

Signed by me at Boston, Massachusetts, this seventeenth day of July, 1912.

GEORGE WALKER.
